UNITED STATES PATENT OFFICE.

CHARLES W. GRUBE, OF PROVIDENCE, RHODE ISLAND.

DESIGN FOR A BUTTON BADGE.

SPECIFICATION forming part of Design No. 24,063, dated February 26, 1895.

Application filed January 29, 1895. Serial No. 536,605. Term of patent 3½ years.

To all whom it may concern:

Be it known that I, CHARLES W. GRUBE, a citizen of the United States, residing at Providence, in the county of Providence, in the State 5 of Rhode Island, have invented and produced a new and original Design for a Button Badge, of which the following is a specification, reference being had to the accompanying drawings, which form a part hereof.

Figure 1 is a front view of my said design and Fig. 2 is a side view thereof.

The leading feature of my design is an ornamental button-front, which is a representation, in miniature, of a bean pot, filled with beans and with a piece of pork, and having on its central exterior surface a triple cross. The bean-pot is represented as having a flat bottom and bulging sides and a somewhat flaring open top, which top is shown as apparently in perspective, thus displaying an elliptical portion in the design, with minute, round

projections therein and also with small, substantially rectangular projections, representing, respectively, the beans and pork, with which the pot is shown as filled. Upon the 25 front of the bean-pot, so represented, is a triple cross, whose upright beam is inclined at an acute angle with reference to the bottom of the design, but whose transverse arms (the central one being a little longer than the 30 other two) are shown as parallel to said bottom. This ornamental front portion is shown at one end of a shank or post, which has at its opposite end a circular disk or back, the whole constituting a button badge. 35

I claim—

The design for a button badge herein described and shown.

CHARLES W. GRUBE.
